DRYING APPARATUS

Gerard Tremblay, Montreal, Quebec, Canada

Application October 31, 1947, Serial No. 783,277
In Canada August 12, 1947

13 Claims. (Cl. 34—133)

1*Introduction*

This invention relates to drying apparatus of the rotary tumbler type, and more particularly to improvements in construction adapting the apparatus to easier handling and better drying as well as versatility of use.

Prior art

Many types of rotary tumbler drying machines have been placed in use but certain disadvantages have prevented their wide household acceptance. For instance, the restricted use of a rotary tumbler type of drier made them an expensive household item, and maintenance plus costly installation and intricate operation placed them beyond the average person.

Objects

The present invention deals fundamentally with these and other disadvantages and aims to provide a thoroughly practical solution by providing a drier of the rotary tumbler type, which is easily and quickly convertible to other drying uses, has simple operation, includes positive controlling of quantity and disposition of air circulation, and also easy access to the working parts in cases where maintenance or replacement of parts is required.

The invention resides in an improved drying apparatus of the rotary tumbler type, having a removable tumbler drum, method and means for removably mounting said drum, and means for controlling the disposition and quality of air circulated through said drum. More particularly, the invention is embodied in a structure which comprises a housing upon which is mounted tumbler driving means, and, contained within said housing are partitions adapted to form a heat chamber. A perforated cylindrical drum constituting the tumbler is removably mounted for rotation within the heat chamber. Driving elements, preferably friction rollers, are suitably mounted on the housing in a position to engage the drum which desirably includes a rim, preferably adjustable laterally, the rim engaging the driving elements, registering openings in the upper housing and the heat chamber are provided for the removal of the drum, and a door fitted to said openings is adapted to form a closure. A second door mounted within said first mentioned door, which provides access to an open end of the drum and contains a rotatably mounted bearing for one end of the drum which is preferably a disc is adapted to mate with and close the open end of the drum. A second bearing

2

member mounted on the opposite end of the drum is adapted to detachably engage a bearing member on one of the partitions of the heat chamber. The applicant prefers to construct the housing in the form of a base casing carrying a motor and the driving elements, and an upper casing carrying the drum supporting mechanism.

According to a preferred embodiment of the invention, there is slidably mounted on the base casing and in communication with the heat chamber, a lint drawer, which is adapted to prevent lint from being recirculated through the heat chamber. The lint drawer includes slots in its base slidably registering with slots in the casing which houses the air circulating apparatus and is thus adapted to control the disposition and quantity of air circulated within the drying apparatus.

Detailed description

Having thus generally described the nature of the invention, particular reference will be made to the accompanying drawings illustrating a preferred embodiment thereof, and in which—

Figure 1 is a side view partially in section showing a preferred embodiment of the apparatus.

Figure 2 is a front view partially in section further illustrating the apparatus as shown in Figure 1.

Figure 3 is an enlarged sectional view of the front pivot bearing 46 as shown in Figure 1.

Figure 4 is an enlarged sectional view of the rear bearing 44 as shown in Figure 1.

Figure 5 is an isometric view of the static rack assembly.

Figure 6 is an isometric view partially in section of the lint drawer 14.

As illustrated by the drawings, with particular reference to Figures 1 and 2, a structure embodying the invention comprises a body portion 10 and a base 12. A seat comprising a rubber strip 14, firmly seats the body 10 upon the base 12.

The body 10 consists of a housing, supported on a framework 16, the framework 16 also supporting heat resistant insulation 18, forming a heat chamber 20. The heat chamber 20 is shaped to substantially enclose a rotatably mounted tumbler drum 22, and a heating element chamber 24. The upper portion of the body 10 includes a frame 34, a hinged cover 26, and a panel 36, forming the back of the body 10 and is removable from the said body to provide access.

The front of the body 10 comprises a removable control panel 38, and a pair of doors, one contained within the other, namely a heat chamber door 40, side hinged and closing on the body

10, and a drum door 42, contained within the door 40, hinged to swing down. A ball bearing mounting 46, fixed to the drum door 42, is adapted to pivotally mount the front of the tumbler drum 22, and a second ball bearing mount 44 is 5 adapted to pivotally support the rear of the tumbler drum 22.

The base 12

The base 12 is supported on the base frames 10 56 and 66. The frame 56 is adapted to support a motor 48 having duplex drives 58 and 60, rubber mountings 50 and 54 being utilized to limit vibration.

Extending above the base 12, mounted on rubber seats 66 and seating upon the frame 88 for the shelf 90, is a roller bearing assembly having a pair of spaced-apart rubber-like rollers 70 adapted to contact an adjustable annular driving ring 238, which encircles the periphery of the tumbler drum 22. Each of the said rollers 70 mount a V belt sheave 72 which is drivably connected by means of a V belt 74 to a driving sheave 76 mounted on the motor shaft 60.

A panel 78, hinged at 80 to the rear of the base sheeting 84 and locking thereon by means of a catch 82, provides access to the motor and drive assembly.

A shelf 90 with sides and back extending downward from the frame 88, is equipped with a bottom having a plurality of ports 92 cut out intermittently along the length and the width of its entire surface, the back portion of the said ported bottom being adapted to entirely cover the top of the air duct 94, allowing for the air passage from the top portion of the machine to the said air duct 94.

The exhaust air duct 94 is framed within the base 12 and extends upwardly into a collar fitting under the shelf 90. The outlet end of the exhaust air duct is framed by a removable collar 98 fitted into an opening in the front sheeting 96 of the base 12, said collar 98 carrying a removable ball bearing mounting 100, in which the shaft extension 106 is rotatably mounted and fitted at one end, namely the end inside of the collar 98, with a fan 108, for exhausting the air from the said duct 94, the other end of the shaft 106 being coupled to the shaft extension 58 of the motor 48 by a coupling 112.

A shield 110 which is adapted to cover the front of the base 12, directs the exhaust air stream toward the floor. The bottom of the base 12 beneath the motor 48 is completely open from the forward frame 56 to the rear frame 56 except for the rails on which the motor-mount 52 is supported. This is to allow for the passage of air into the lower portion of the outer housing from which it is drawn to the upper portion of the housing, between the housing and an inner heat chamber 20.

The body 10

The heat chamber 20 is fabricated on a framework 16 and covered with an insulation 18, the heat chamber being formed to enclose the drum 22, an air intake passage adjoining the element 24, between the framework 16 and the back panel 36, and an air exhaust passage formed by the opening at the bottom, also an open front which is closed by the heat chamber door 40.

The outside shell of the body is framed at the top, said frame 34 supporting a cover 26, hinged at 28 to the said frame 34, the cover being substantially rectangular in shape, and adapted to close the rectangular opening formed by the

frame 34. The cover 26 is equipped with a rubber seating 32, which is fixed to the under part of the flange of said cover and provides for airtight closure upon the frame 34. A pair of folding fasteners 30, fixed at one end to the cover 26 and to the frame 34 at the other end, is adapted to keep the said cover ajar when lifted.

The heating element chamber 24

The heating element chamber 24 consists of an insulating box 134, completely covering the heating unit at the top of the heat chamber 20. Louvers 136 are cut out from the sides of the said box 134, and provide for air passage from the air intake to the heat chamber 20, causing the air to flow past a plurality of electric elements or lamps 148, which are screwed into sockets 150 mounted on a reflector bridge 152, the said reflector bridge being fastened to the front and back walls of the box 134. Guide frames 138 are fastened to the side walls, on the outside of the box 134, said guides are spaced from the walls to slideably admit a pair of removable screens 140, which cover the louvers 136. The said box 134 is equipped with a cover 142, hinged at 144, and is held down by means of a catch 146 on the front of the box 134. The complete unit including the box 134, with its cover 142, the reflector bridge 152, with its sockets 150, and electric elements or lamps 148 is adapted to be removed as a unit.

The control panel 38

The control panel 38 is removable from the body 10 and mounts a three-way switch 166 controlling the heating elements or lamps 148, for off—low—medium and high heats, a pilot light 168 which lights up when the elements are lit, an on-off motor switch 170, a time control switch 172 with bell announcer, a thermostatic control 154 with a range of 0 to 300° F.

The incoming power line is passed through a fuse box with a main switch (not shown on drawings) both installed at the back of the framework 16, to the control panel 38. A thermostat bellow or coil spring element 169, placed within the heat chamber 20, is controiled by the thermostatic control of the panel 38 and is adapted to regulate the air heat in the heat chamber 20, by shutting off the elements 148 at any temperature desired.

The time control switch 172 is connected to the motor switch 170.

The heat chamber and drum doors 40 and 42

Side hinged to the body shell 10 is a substantially square heat chamber door 40, with insulation 208, having a substantially round drum loading door 42, with insulation 210, downwardly hinged at 178, and contained within its framework, both doors having latching means 188 and 190, and equipped with rubber sealing strips 184 and 186 respectively for securing an airtight closure. Centrally located on the inside of the door 42 is a pivot bearing 46, to which is rotatably mounted a flat disc-like member 192, with flanged circumferential edge 194, said flanged edge 194 carrying a rubber gasket 196, adapted to lap into the open face of drum 22, sealing the front of the drum by the contact of the gasket 196 with the annular rolled edge 222 of the facing 212 of the said drum 22.

The disc-like member 192, pivotally mounted for rotation on the mounting 46, provides a closure for the drum 22 as well as a front bearing when the drum is rotating. This disc member 192 is mounted on the pivot 198 equipped with ball

catch 200 which snaps past the inner face of the ball bearing 202 bushed by rubber ring 204 around its outside face, and retained by plate 206 inside the mounting 46.

The tumbler drum 22

The tumbler drum 22 has a solid annular backing 212 with an inwardly extending flange 214 to which is welded the perforated body portion 216. On the front portion of the drum 22 is an annular facing 218 carrying an inwardly extending flange 220 on its outside periphery, which is likewise welded to the perforated portion 216. The inside periphery formed by the inside rolled edge of the facing 218 is adapted to fit with the rubber gasket 196 on the pivotally mounted disc member 192 of the small door 42.

Axially in line with the pivot of the pivotal mounting 46, but on the inside of the drum backing 212, is the back bearing 44 which is adapted to engage with the bearing pivot 224, which is fixed to the frame 16 extending into the heat chamber 20. A double ball-catch 226, by choice located on the pivot 224, is adapted to catch behind the inside face of the ball bearing 228, which is housed in a rubberlike bushing 230, and retained by the plate 232 fastening to the back of the annular backing 212 of the drum 22.

Fixed to the inside surface of the perforated drum body 216, annular backing 212 and annular facing 218, are fitted a plurality of wooden lifters 234, covered with heat and water resistant covering 236.

On the outside of the body portion 216 of the drum 22, is a narrow annular driving ring 238, which is detachably fastened to the perforated portion of the body by means of screws which pass through the perforations of the drum into the wooden lifters 234. If desired, by removal of these screws, the driving ring 238 can be moved axially of the drum body 216 and the screws reinserted through other perforations in the drum into the wooden lifters 234. This allows the position of the driving ring 238 to be adjusted so as to equalize wear on the driving rollers of the machine.

The roller drive

Mounted on the shelf framework 88, and adapted to extend into the body portion of the assembled dryer, is a roller bracket 62, having a pair of spaced-apart rollers 70, with shaft extensions at both ends rotatably mounted on roller bearings 64, the mountings of which are fixed to the said bracket 62. These rollers 70 are adapted to frictionally contact the driving ring 238 attached to the drum 22.

The bracket 62 on which the rollers 70 are mounted includes a flat base portion, which is mounted on the frame work 88, and integral flanges extending vertically upwards from the base portion at each end to provide spaced apart opposed supporting members for the roller bearings 64 between which the rollers 70 are supported for rotation. The flange of the bracket 62 adjacent the front of the housing includes a semi-circular cut-out to provide clearance for the outer periphery of the drum body 216. The base portion of the bracket 62 also includes a circular opening which is placed in register with the rear portion of the lint drawer 114.

The rollers 70 are mounted between the flanges of the bracket 62 so as to extend axially at each side of and beneath the drum body. The inner ends of the shaft extensions of the rollers 70 extend beyond the rear flange of the bracket 62 to

adjacent the rear wall of the outer housing and the roller driving V-belt sheaves 72 are secured to these shafted ends.

An annular collar 68 is fitted to the bracket 62 and encircles the opening located in its base, between the rollers 70. This collar extends upward to clear the perforated portion 216 of the drum 22 and is adapted to guide the air to the lint drawer 114.

The lint drawer 114

The lint drawer 114 is adapted to slide into the shelf 90 at the top of the base 12, and has an open top that corresponds with the opening in the base of the roller bracket 62, and a closed top portion bending at 90° angle to extend downward and form a front panel for the said drawer 114. Fixed to the front panel and adapted to provide a means of pulling said drawer from the shelf, is a handle 132, under which, protrudes the head of small, sliding spring loaded bolt 130, through a slot in the front panel, where said bolt 130 slides up and down to release or lock the drawer 114 in the desired position, said bolt 130 catching in notches provided at the top flange of the shield 110, the bottom of the drawer 114 having two sets of ports cut from its surface, each set taking up about half the length of the said bottom. The first set of ports 116 are located at the back of the drawer 114 and are covered by a screen 120, the second set of ports 118 are located under the closed portion of the drawer 114, the two sets of ports being separated by a wall 122 hinged at 124 to the top surface of the drawer 114 and being retained by a catch 126.

The set of ports 116 are in register with the ports 92 in the shelf bottom when the drawer 114 is fully pushed in or flush with the shield 110, having the drawer 114 in this position the set of ports 118 are out of register with the ports 92 thereby closing this section of the drawer 114 and causing the air to be drawn entirely from the heating chamber 20.

When the drawer 114 is pulled out the distance equivalent to the width of one of the ports 92, the set of ports 118 are in register with the ports 92 and the set of ports 116 are out of register with the ports 92 stopping the air flow in the heat chamber 20 and drawing the air from the front of the base 12.

When the drawer 114 is in a position intermediate between the two positions as described, the air supply is drawn half from the heating chamber 20 and half from the front of the base 12.

The three positions are indicated by markings in the top of the drawer 114 as shown as 128.

The motor 48 (twin shafts)

The power unit of the assembly consists of an electric motor 48 equipped with a standard rubber mounting 50, the shaft of which extends from both ends as at 58 and 60. On one end of the shaft namely 60, a sheave 76 is fixed to accommodate a V belt 74. This belt passes around the sheave 76 and the two pulleys or sheaves 72, which are adapted to drive the rubber rollers 70. The motor 48 is slidably mounted on a motor mounting 52 spanning the frame 56 of the base 12, said mounting being equipped with rubber pads 54. The opposite end of the shaft, namely 58, is coupled by coupling 112 to the shaft extension 106, upon which is mounted the fan 108. In the case of a single shaft motor being used to drive the dryer, a twin groove type V belt sheave mounted on the motor shaft extension is adapted to drive the rollers from one groove and the ex-

haust fan from the other with the motor away from the centre and located at either side of the base.

Thermostat control

The thermostat element 160, fixedly attached to the back of the heat chamber framework 16, and protruding inside of the heat chamber 29, where it reacts to the temperature existing inside of the said heat chamber, is adapted to be controlled by means of a plate wheel 162, on which is mounted a pair of mercury bulbs 164, connected directly to the power line supplying the heating elements or lamps 148. The wheel 162 is connected to a small wheel 156 at the end of the control knob 154 stem or shaft, by means of a cable 158 which encircles both wheels.

The shelf assembly

The shelf assembly is composed of a shelf base 244, side members 248, and the shelves 252.

The shelf base 244, includes legs extending downwards at 90° angle with the top that are sufficiently spaced apart to span the rollers 78 at each side, so that they may slideably fit between the outside of the rollers 78 and the vertical portion at the bottom of the heat chamber 16, to rest on the floor provided by the base framework 86. A tube 246, having an inside diameter of suitable dimensions to slideably admit the leg of the side member 248, is fixed to each corner of the shelf base 244, said tubes being adapted to support the side members 248 in an upright position.

The side members 248 are rectangular in shape, having two legs extending from the rectangular framework, said legs being adapted to fit into the tubes at the corners of the shelf base 244, and are equipped with a number of Z section strips 250, said strips being spaced apart to adjust the shelves 252 at different heights along the length of said side members 248.

Operation

After a short pre-heating period, during which no air is allowed to pass through the heat chamber, by pulling out the lint drawer 114 to the "closed" position, the clothes to be dried are thrown loosely into the interior of the tumbling drum 22, through the small door 48. The lint drawer 114 is adjusted to allow the proper quantity of air to be drawn through the drum by the fan. Suitable adjustments are made on the thermostat and the time switch, the door is closed, the motor is started, and the heater elements are turned on to the desired degree of heat, by means of the switch 166.

The air entering through the open bottom of the casing between the front and rear frames 56 is then drawn through the space between the framework 16 and the back panel 36 of the assembly into the heating element chamber 24, and past the heating elements 148, and thence through the tumbling drum 22, and out through the exhaust air duct 94, after having passed through the screen in the lint drawer 114. The exhausted air is then deflected by the shield 115 out through the open bottom of the machine at the front.

By simply removing the tumbling drum, the machine can be used to dry objects which do not need tumbling. A shelf assembly, which is illustrated in Figure 5, is inserted in place of the tumbler drum and stands on the top of the framework 86. This shelf assembly includes adjustable shelves, on which can be placed many fragile ob-

jects such as dishes or glassware, etc., or any article that does not need tumbling, or that cannot be tumbled in a revolving drum.

Advantages

The machine as described, provides many advantages over the prior art which will be outlined briefly as follows.

The machine being simple in structure provides easy operating for the "lady of the house" and the two-part construction of the machine provides an advantage that it can be easily used in a small apartment in which door space is often restricted. The construction of the machine, providing for a heat chamber within an outside shell, with an air space between, eliminates any chance of heat discolouring a wall behind the machine or the possibility of one burning one's self on the machine while it is in operation. The removable panel in the rear of the upper portion of the machine provides easy access to the working parts of the machine in case of any trouble, and the swing door in the lower portion provides easy access to the mechanical portions of the dryer should trouble develop. This feature alone cuts down a lot on time for service men while doing maintenance.

The construction of the tumbler, namely that the perforated drum is adapted to clear the fixed driving rolls by the thickness of the driving ring, means that any buttons etc., which penetrate the perforations in the drum are not damaged by contact with the rollers, and likewise the rollers are not damaged by contact with the buttons. The lifters being made of wood and covered with metal, and attached to the perforated portion of the drum permits the easy replacement of the lifters by simply removing wood screws. The attachment of the driving ring to the outside periphery of the drum by means of wood screws, passing through the perforations in the drum, allows for the shifting of the driving ring across the width of the drum, thus preventing undue wear in any one spot on the rubber friction rollers. The entire construction, including the insulation, the V belt, the ball-bearing mountings for all movable parts, provides for vibrationless and quiet operation, which would be of an advantage in a small house or apartment.

A further advantage is provided by the method in which the heating elements, which are ordinary service heating elements are screwed into ordinary sockets, thus providing for the adaptation to lamps or other types of explosion-proof heating elements which would readily transform the assembly into a drying unit used for dry cleaning. The adaptation of thermostatic and time control are further advantages in that the operator does not have to provide his undivided attention while it is operating, but can leave the machine and it will maintain an even and not dangerous temperature and automatically close off as the clothes dry out.

A still further advantage of this dryer, made possible by the removal of the tumbling drum is to provide a static shelf for drying articles such as dishes which do not need tumbling. The welded construction of the drum provides a drum of far superior strength with the additional feature of not having outstanding flanges. The ability of the operator to control the quantity of air passing through the drum by means of the lint drawer, provides distinct advantage over prior art machines in that no other form of air control gear is added.

A further advantage of the applicant's structure is the portability of the machine, in that no pipes are necessary to drain off surplus water, the water being absorbed by evaporation due to the heat from the heating elements.

It will be understood that, without departing from the spirit of the invention or the scope of the claims, various modifications may be made in the specific expedients described. The latter are illustrative only and not offered in a restrictive sense, it being desired that only such limitations shall be placed thereon as may be required by the state of the prior art.

The sub-titles used throughout the specification are merely to simplify reference thereto and should otherwise be disregarded.

I claim:

1. A drying apparatus comprising, an outer casing, an inner casing mounted in spaced-apart relationship with said outer casing to constitute a heat chamber, said inner and outer casings being provided with registering openings, a main door adapted to form a closure for both of said openings, said main door having an opening therein, a secondary inner door adapted to form a closure for said main door opening, a cylindrical drum mounted for rotation within said inner casing, said drum having an imperforate back wall, the peripheral surface of the drum having openings adapted to allow air to pass freely therethrough, a front wall on the drum having an opening in register with the openings in said inner and outer casings, a closure member for said drum opening, opposed bearing assemblies on the rear wall of said inner casing and the inner face of said secondary door respectively adapted to engage the axial faces of said drum closure member and said drum back wall thereby to support said drum for rotation, driving means within said outer casing adapted to rotate said drum, the inner casing including openings constituting passage ways for the circulation of air within said casing, means for controlling said circulation of air, means for heating said air, means to exhaust air from said inner casing, said outer casing including openings constituting passage ways adapted to allow air to be drawn into and exhausted from said inner and outer casings, the openings in said outer and inner casings closed by said main door being sufficiently greater in size than the outer diameter of said drum to allow said drum to pass freely therethrough, said secondary door being hingedly connected to said main door, said drum closure member being mounted for rotation on said secondary door bearing assembly whereby the opening of said first door also opens said second door and drum closure member to provide an opening through which said drum may be inserted or removed, and the opening of said second door, when said first door is closed, also opens said drum closure member to provide an opening through which said drum may be charged.

2. A drying apparatus, according to claim 1, in which said rear wall bearing assembly comprises, a stub shaft fixed to the wall of the heat chamber, a ball catch on said shaft, a roller bearing, a substantially dome shaped member centrally fixed to the solid back of said drum, a resilient mounting attaching said roller bearing to said dome member, said roller bearing adapted to slip onto said shaft and be detachably retained thereon by said ball catch.

3. A drying apparatus, according to claim 1, in which said means for controlling the circula-

tion of air through said heat chamber comprises, a boxlike drawer, said drawer being slidably mounted on a frame, and having a closure over a portion of its top face, a wall hingedly mounted to said closure and extending downwards to form a complete closure of the front portion of said drawer, said drawer also having in the bottom portion a plurality of spaced apart elongated ports, said ports masked by a screen in the rear portion of said drawer, said frame having a plurality of spaced apart elongated ports adapted to workably register with said drawer ports, means to position said drawer to control quantity and disposition of said air circulation.

4. A drying apparatus, according to claim 3, in which the means to position said drawer constitutes, a spring-loaded bolt slidably mounted in the front portion of said drawer, said bolt being adapted to engage any of a plurality of holes in said frame, wherein said ports are placed in predetermined registration according to the spacing of said holes.

5. A drying apparatus, according to claim 1, in which the removable rotatably mounted drum comprises, a cylindrical perforated body, a solid circular backing, an annular facing, said backing having an inwardly extending flange on its outside periphery, and being fixedly attached to said body, said annular facing having an outwardly extending rolled edge on its inside periphery and an inwardly extending flange on its outside periphery fixedly attached to said body, said rolled edge framing a centrally disposed opening in said annular facing adapted to engage said drum closure member rotatably mounted on said second door, a plurality of lifting members, said lifting members being radially disposed across said body and being detachably fixed therein.

6. A drying apparatus as claimed in claim 1 in which said outer casing is divided into two portions comprising a base portion and an upper portion, said base portion constituting a housing for said drum driving means, said air exhausting means, and said air circulation means, said upper portion constituting a housing for said heat chamber, said rotatably mounted drum and said air heating means.

7. A drying apparatus according to claim 1 in which the bearing assembly mounted on the inner face of said secondary door comprises a bearing rotatably fixed on said door, said drum closure member being mounted for rotation on said bearing and being adapted to mate with the periphery of said opening in said drum, thereby forming a closure and a rotatable bearing for said drum.

8. A drying apparatus according to claim 1 wherein the drum driving means comprises a pair of driving rollers mounted within a lower portion of the outer casing, means to drive said rollers, an adjustably mounted driving ring mounted on said drum, said ring surrounding the outside periphery of said drum and being adapted to be driven by frictional contact with at least one of said rollers, said ring being adapted to be fixed in any of a plurality of positions extending across the width of said drum, said rollers extending substantially the full width of said drum.

9. In a drying apparatus having an outer casing, an inner casing mounted in spaced apart relationship with the outer casing to constitute a heat chamber, said inner and outer casings being provided with registering openings, a main door adapted to form a closure for both of said openings, said main door having an opening

therein, a secondary inner door hingedly connected to said main door adapted to form a closure for said main door opening, a cylindrical drum mounted for rotation within said inner casing, said drum having an imperforate back wall, the peripheral surface of the drum having openings adapted to allow air to pass freely therethrough, the front wall in the drum having an opening in register with the openings in the inner and outer casings, a closure member for the drum opening, the combination comprising opposed bearing assemblies on the rear wall of the inner casing and on the inner face of the inner secondary door respectively, said secondary door bearing assembly being adapted to support and retain said closure member for rotation and said rear wall bearing assembly being adapted to connect the drum back wall thereby to support the drum for rotation, means adapting the drum to be rotated, the drum located centrally of the inner casing so to be accessible for heated air circulating therethrough, the openings in the outer and inner casings closed by the main door being sufficiently greater in size than the outer diameter of the drum to allow the drum to pass freely therethrough.

10. A drying apparatus according to claim 9 in which the bearing assembly mounted on the inner face of said secondary door comprises a bearing rotatably fixed on said door, said drum closure member being mounted for rotation on said bearing and being adapted to mate with the periphery of said opening in said drum, thereby forming a closure and a rotatable bearing for said drum.

11. A drying apparatus, according to claim 9, in which said rear wall bearing assembly comprises, a stub shaft fixed to the wall of the heat chamber, a ball catch on said shaft, a roller bearing, a substantially dome shaped member centrally fixed to the solid back of said drum, a resilient mounting attaching said roller bearing to said dome member, said roller bearing adapted

to slip onto said shaft and be detachably retained thereon by said ball catch.

12. A drying apparatus according to claim 9, wherein the drum driving means comprises a pair of driving rollers mounted within a lower portion of the outer casing, means to drive said rollers, an adjustably mounted driving ring mounted on said drum, said ring surrounding the outside periphery of said drum and being adapted to be driven by frictional contact with at least one of said rollers, said ring being adapted to be fixed in any of a plurality of positions extending across the width of said drum, said rollers extending substantially the full width of said drum.

13. A drying apparatus, according to claim 9, in which the removable rotatably mounted drum comprises, a cylindrical perforated body, a solid circular backing, an annular facing, said backing having an inwardly extending flange on its outside periphery, and being fixedly attached to said body, said annular facing having an outwardly extending rolled edge on its inside periphery and an inwardly extending flange on its outside periphery fixedly attached to said body, said rolled edge framing a centrally disposed opening in said annular facing adapted to engage said drum closure member rotatably mounted on said second door, a plurality of lifting members, said lifting members being radially disposed across said body and being detachably fixed therein.

GERARD TREMBLAY.
